UNITED STATES PATENT OFFICE.

OTHO M. OTTE, OF JAMESTOWN, NEW YORK.

SHEET-METAL CONSTRUCTION.

1,249,813.

Specification of Letters Patent. Patented Dec. 11, 1917.

Application filed October 18, 1916. Serial No. 126,304.

To all whom it may concern:

Be it known that I, OTHO M. OTTE, a citizen of the United States, residing at the city of Jamestown, in the county of Chautauqua and State of New York, have invented certain new and useful Improvements in Sheet-Metal Constructions, of which the following, taken in connection with the accompanying drawings, is a specification.

The invention relates to a novel manner of attaching sheet metal plates, particularly paneling and similar constructions; and the improvement consists in providing an offset in or on the sheet metal plate to which the molding or other sheet metal work is to be attached, which offset is shaped in its outer portion to conform to the contour of the molding or sheet metal work to which it is to be attached so that the contacting sheets of metal may be attached to one another by spot welding, an opening being provided in the sheet metal plate through which one of the points of the spot welder may be inserted, the other point being applied on the outer surface of the molding or other sheet metal work; and the invention consists in the novel features and combinations herein-after set forth and claimed.

In the drawings, Figure 1 is a sectional perspective view of a portion of a sheet metal construction as, for example, a door or panel work, the sectional view being shown directly through the offset thereby showing said offset shaped in its outer portion to conform to the contour of the molding; and Fig. 2 is a sectional perspective view of the sheet metal plate without the molding showing the entire offset as struck from the metal plate and shaped for the molding shown in Fig. 1; and Figs 3 and 4 and 5 and 6 show sectional perspective views of different shaped offsets, each conforming to the contour of the molding to be attached, Fig. 5 showing in dotted outline one of the welding points extending through the opening in the sheet metal plate made by striking out the offset. Fig. 7 is a sectional perspective view with the section crosswise of the sheet metal plate and the molding, said molding being of so great depth as to prevent the use of an offset, as shown in Figs. 1-6; and Figs. 8 and 9 showing the manner in which the offset is cut and struck up into the lug or truss form, each of the parts of the offset forming, as it were, struts which are each attached to the inner side of the molding by spot welding, the molding thereby completing the truss

construction, Fig. 9 showing a plan view of the manner of cutting the sheet metal before bending it up into the conforming offset lugs. Fig. 10 is a lengthwise sectional view at line X—X in Fig. 3 showing a series of spaced conforming offsets welded to the sheet metal molding. Fig. 11 is a perspective view of the sheet metal plate without the molding showing a modification in the construction of the conforming offsets in which the offset is made as a conforming clip and spot welded to the metal plate, a hole being provided in said plate beneath the conforming portion of the clip; and Fig. 12 is a sectional perspective view of the same construction with the molding attached thereon, said molding being broken away to show the one-half of the conforming clip welded to the metal plate; and Fig. 13 is a front perspective view of the conforming metal clip before it is welded to the metal plate. Figs. 14, 15 and 16 show perspective views of the different portions of the conforming metal clip showing a modification of the construction shown in Figs. 7, 8 and 9, applying the conforming metal clip to the deep construction instead of the conforming offset. Fig. 17 is a sectional view at line Y—Y in Fig. 15 showing a series of conforming metal clips spot welded to the sheet metal plate as well as to the molding.

Like characters of reference refer to corresponding parts in the several views.

The numeral 10 designates a sheet metal plate provided with a lengthwise angle 11 within which the molding 12 is usually attached though the angle 11 is not essential to this method of attachment. This method of attachment is used more often in attaching molding in panel work and similar constructions, though it may be used in attaching any spaced sheets of metal.

The molding 12 may be left without in-turned flanged edges as shown at 13 or may have inturned flanged edges 14 when desired though they are rarely necessary since the manner of attachment forms a perfect joint when properly alined so that the joint takes a smooth finish and the manner of attachment is so strong that it holds the molding 12 rigidly in line.

The preferred method consists in striking up an offset 15 whose outer portion or face 16 is shaped to conform to the contour of the molding or other sheet metal work 12, which in Figs. 1, 2, 11, 12 and 13 is ogee; in Figs. 3 and 4 it is slightly inclined, and

in Figs. 5, 6, 7, 8, 14, 15 and 16 it is horizontal.

The striking up of the offset 15 provides an opening 17 into which the point 18 of the 5 welder may be inserted so that the opposite point may be applied on the outer side of the molding 12 thereby quickly and easily spot welding the two conforming sheets of metal making them one, and rigidly attaching 10 the molding 12 to the sheet 10, it only being necessary to have care in fitting the molding 12 to the sheet 10 before spot welding.

Where the molding or other sheet metal 15 work is too deep, as in the molding 19 in Fig. 7, so that the sheet metal cannot be stretched sufficiently to form a contacting offset for the deep molding 19, the sheet metal plate 10 is cut as shown in Fig. 9 with 20 a central cross cut 20, providing two lugs or struts 21, the upper ends 22 of which are shaped to conform to the contour of the inner wall of the molding 19. It is apparent that no matter how deep the molding or 25 sheet metal work 19 may be, the pair of offset struts or lugs 21 of sufficient depth may be cut from the sheet of metal 10 and each of the two outer ends 22 being spot welded to the deep molding 19 forms a 30 strong and rigid attachment thereto which holds the molding firmly in place so that it can be finished the same as though it were a part of the plate 10.

In attaching a strip of molding spaced 35 offsets 15 or 21 are struck up from the sheet of metal 10 sufficiently close to one another to hold the molding 12 firmly in line and provide a strong attachment to the sheet metal plate 10. This manner of attachment 40 for molding and other hollow sheet metal construction can be used wherever the inner side of the sheet metal plate 10 is not exposed, as for example in all hollow door or panel work and forms an exceedingly simple and durable method of attachment having 45 great strength, since the molding 12 cannot be removed from the sheet of metal 10 without destroying the offset 15 or 21 to which it is firmly welded. It also adjusts 50 it so rigidly that there is no opportunity for working loose and rattling upon sheet metal car work and similar constructions.

The modification shown in Figs. 11-17 inclusive attains the same purpose in substantially the same manner by means of 55 clips 23 which are attached by spot welding each end 25 to the sheet metal plate 10 over a hole 24 through which the point of the spot welder may be inserted for spot welding, the raised portion 16 conforming to the 60 similarly shaped molding 12 the same as the offset 15. The only difference between this modification and the preferred offset form

15 is that the separate clips are bent to the required shape and attached by spot welding 65 instead of being struck out from the sheet metal plate 10.

The striking out of the offset 15 from the sheet metal plate 10 is the simpler and easier method, since it forms the hole 17 and the 70 offset 15 with one movement of the die, thereby quickly and easily attaining the purpose, the ends of the offset 15 being integral with the plate 10, whereas the clips 23 have to be spot welded to the plate 10 and the 75 holes 24 have to be punched specially. The deep form of the modification is shown in Figs. 14, 15 and 16, in which the clips 26 are spot welded at one end to the plate 10 and at the other to the molding 19, and, preferably, two openings 24 are provided beneath the ends 22 for spot welding.

I claim as new:—

1. In sheet metal construction, a sheet metal plate having an angle therein, a strip 85 of sheet metal molding fitting in said angle, and spaced offset portions on said plate a spaced distance from said angle and shaped to fit against said molding, said molding being secured to the plate by attachment to 90 the offset portions.

2. The herein-described method of attaching hollow metal members to the front face of a base sheet from the rear face of said sheet and at a point interiorly of the member, which consists in first forming a hole in the sheet so as to be concealed by said member, then in providing a connection extending from the sheet to the member interior, and finally in effecting securing of the 100 connection to the member through said hole.

3. The herein-described method of attaching hollow metal members to the front face of a base sheet from the rear face of said sheet and at a point interiorly of the member, which consists in first striking up a part 105 of the sheet to form a hole concealed by said member and a connection which latter is engaged with the inner face of the member, and finally in effecting securing of the 110 connection to the member through said hole.

4. In sheet metal construction, a plate having an angled part, molding fitted in the angle and having its approximate central parts spaced from the plate, and connections bridging the space between the approximate central parts of the molding and plate and secured to each to positively attach the molding to the plate.

In testimony whereof I have affixed my 120 signature in the presence of two witnesses.

OTHO M. OTTE.
